Primary Examiner — Cynthia Ramirez(74) *Attorney, Agent, or Firm* — Kim and Lahey Law Firm, LLC; Seann P. Lahey(57) **CLAIM**

The ornamental design for a utility cart, as shown and described.

DESCRIPTION

FIG. 1 is a top perspective view of the utility cart showing my new design;

FIG. 2 is a bottom perspective view thereof;

FIG. 3 is a first end elevational view thereof;

FIG. 4 is the other end elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the figures show environment and form no part of the claimed design.
